UNITED STATES PATENT OFFICE.

REUBEN L. TAYLOR, OF MANCHESTER, IOWA.

IMPROVEMENT IN WIRE-SPlicing TOOLS.

Specification forming part of Letters Patent No. 178,884, dated June 20, 1876; application filed April 13, 1876.

To all whom it may concern:

Be it known that I, REUBEN LINCOLN TAYLOR, of Manchester, Delaware county, State of Iowa, have invented a new and useful Tool or Wrench for Splicing Wire for Telegraphs, Fences, and other uses, which is fully set forth in the following specification, reference being had to the accompanying drawings.

The object of my invention is to facilitate the splicing of wire for various purposes, and particularly for telegraphs, fences, and other purposes.

In the accompanying drawings, Figure 1 is a plan, and Fig. 2 a side elevation, of my invention.

In these drawings, A is a bar of iron or steel, made in the form shown, or in such other form as will answer the purpose. The upper end is made wider, and about half the thickness of the other part, forming a recess, B, with a shoulder at C, against which recess and shoulder the wire lies when being spliced. The shoulder C extends but part way across the recess B, which recess extends to the shoulder D, against which shoulder the wire lies as it is being coiled, with the wrench around the straight wire to which it is being spliced. The hole E is made large enough for the wire to slip freely through it as it is wound around the wire being spliced.

I make a curved depression, H, opposite the

shoulder C and hole E in the recess B, for the wire to lie in as it is coiled around the straight wire.

To use my invention the wires to be spliced are laid parallel, close together, and gripped by a hand-vise or a pair of pinchers to hold them firmly with one hand, when the ends are turned off to about a right angle to the parallel wires with the other hand, when the hole in the wrench is put over one of the ends turned off, and brought down to bring the parallel or straight wire against the shoulder C, when the wrench is moved, so as to wind the end bent off at a right angle around the parallel wire. When this is done the wrench is put over the other end bent off at a right angle, and it is wound in the same manner, and the splice is complete.

What I claim as my invention is—

1. The above-described tool for splicing wire, having an apertured recess, B, with shoulders C and D, as and for the purpose described.

2. The combination of the apertured recess B, having shoulders C and D, with the recess H, as and for the purpose set forth.

REUBEN LINCOLN TAYLOR.
